SURF BOARD

Janet L. Marshall, 219 Monte Vista Ave.,
Costa Mesa, Calif. 92626

Filed Apr. 24, 1970, Ser. No. 22,639

Term of patent 14 years

Int. Cl. D21—03

U.S. Cl. D71—1

FIG. 1 is a top plan view of a surf board embodying the invention;

FIG. 2 is a side view of the surf board;

FIG. 3 is a view in bottom elevation of the surf board in FIGS. 1 and 2;

FIG. 4 is a front view of the surf board;

FIG. 5 is a rear view of the surf board; and

FIG. 6 is an enlarged fragmentary view of the mat that covers a portion of the upper surface of the surf board and which is visible in FIGS. 1, 2 and 5.

I claim:

The ornamental design for a surf board, substantially as shown and described.
